UNITED STATES PATENT OFFICE.

CONRAD JOEST, OF TOLEDO, OHIO, ASSIGNOR TO THE KENT-OWENS MACHINE CO., OF TOLEDO, OHIO, A CORPORATION OF OHIO.

DIE HEAD FOR THREAD-CUTTING TOOLS.

Application filed September 30, 1921. Serial No. 504,283.

The invention relates to die heads of that type used upon automatic machines for thread cutting and similar operations. Such constructions comprise essentially a rotary head, a plurality of thread-cutting tools or chasers radially movable in said head and concentric to the axis thereof, means for locking the chasers in an inner position of adjustment for the performance of the threading operation, and means for automatically releasing and retracting the chasers when the desired length of thread has been cut.

It is the object of the present invention to simplify the construction required for the performance of the essential function as above described and also to render the operation more positive and accurate. Particularly, it is an object to avoid the use of cams and to so design the parts that they may be manufactured by simple machining operations. With these objects in view the invention consists in the construction as hereinafter set forth.

In the drawings:

Figure 1 is an elevation of the die head; Figure 2 is a longitudinal section on line 2-2 of Figure 8;

Figure 3 is a similar view on line 3-3 of Figure 8;

Figure 4 is a cross-section on line 4-4 of Figure 3;

Figure 5 is a longitudinal section on line 5-5 of Figure 8;

Figure 6 is a cross-section on line 6-6 of Figure 3;

Figure 7 is an end elevation; and Figure 8 is a cross-section on line 8-8 of Figure 3.

A is a cylindrical member having a concentric axial bore B therethrough and a series of radially extending slots or guide-ways at one end thereof. These slots or guide-ways C are preferably of T-form extending from the periphery to the bore and as shown they are four in number. D is a shank member, the forward end of which slidably engages the bore B, and E is a flange or collar on the shank which forms an abutment for the inner end of the member A. The member A is further provided with a series of longitudinally extending bores F, F', G, H and I. The bores F and F' form recesses for receiving studs J and J' projecting from the flange E on diametrically

opposite sides thereof. K and K' are springs sleeved upon the studs J and J' and abutting at one end against heads on said studs and at their opposite ends against bushings L and L' having a threaded engagement with the member A. The studs J and J' are preferably threaded to engage nuts M and M' and the whole arrangement being one in which the member A is yieldably pressed towards the flange E by the tension of the springs K. Surrounding the member A and longitudinally slidably engaging the same is a sleeve member N having an internal annular groove N' near its forward end. This groove has the oppositely inclined faces N² and N³ which are concentric with the axis of the tool and form opposed cones. O are the chasers or thread cutting tools which slidably engage the radial T-shaped guide-ways C and are held from disengagement by blocks O' engaging the head of the T slot, being secured by the screws O². The outer ends of the chaser blocks O are bevelled at O³ at the same inclination as the cone face N² so that a longitudinal movement of the sleeve N in the direction of the shank will simultaneously bear upon all of the chasers O and move the same equally radially inward. The outward movement of the chaser blocks is also positively effected by the longitudinal movement of the sleeve N in the opposite direction. This is accomplished through the medium of thrust pins P which slidably engage bors in the member A extending obliquely both with respect to the axis of the tool and radial lines from said axis. The inner end of each pin engages a notch Q in the chaser block and bears against an obliquely inclined face Q'. The outer end of each pin is in proximity to the conical face N³ and therefore the outward movement of the sleeve N will effect a longitudinal inward movement of the pin P, which in turn, by its engagement with the oblique face Q', will cause a radially outward movement of the chaser block.

To secure exact dimensions in the work the chaser blocks must be moved inward to an exactly predetermined position and for variation in the work this inward limit must be correspondingly varied. I have provided a simple form of adjustable limiting means comprising a stop collar R which has a threaded engagement with the inner end of the sleeve N. The collar R has the internal

22
 5 annular groove R' forming a shoulder for engaging a locking dog S radially movable in a recess S' in the member A. This dog is yieldably pressed outward by suitable means such as spring S² and is drawn inward by a trip member T. The latter is in the form of a pin which is secured in a bore in the flange E and projects into a registering bore in the member A intersecting the recess S'. The dog S is also slotted for the passage of the pin T therethrough. T' is a portion of the pin T which is reduced in diameter and of conical form, and S³ is an oblique face at the inner end of the slot in the dog S which is engageable with said conical portion T'. These several parts cooperate to cause the radial inward movement of the dog S against the tension of the springs S² whenever the member A is moved 10 longitudinally outward with respect to the shank D. Such a movement will cause the conical portion T' of the pin T to ride over the oblique portion S³ of the dog S, and consequently, will draw the said dog radially inward.

25 The sleeve N is normally held in its outward position by the tension of springs U which are located in the bore G in the member A. One end of each of these 30 springs bears against a threaded plug V which closes the end of said bore, while the opposite end of each spring bears against a radially inwardly extending pin W secured to the sleeve N. Thus the tension of 35 the springs U is exerted to hold the sleeve N at its outward limit of movement at which the pins W abut against the ends of the bore G. On the other hand, these 40 springs will yield to permit the movement of the sleeve N inward. The means for effecting the inward movement of the sleeve consists of a lever X extending through a slot X' in the sleeve and having a ball X² thereon for forming a piv- 45 otal bearing. The inner end of the lever X has a ball X³ which engages a suitable fulcrum recess in the member A and the effect of moving the lower end of the lever X inward is therefore to slide the sleeve N inward on 50 the member A. The amount of movement is sufficient to bring the groove R' into registration with the dog S, whereupon the springs S² will move said dog upward into engagement with the shoulder formed by 55 said groove. The lever X is held from accidental disengagement by a spring latch consisting of a ball Y in the bore I, which is pressed against the ball X³ by a spring Y' 60 abutting against a plug Y² at the outer end of said bore I.

65 In operation, the die head is mounted in a suitable automatic machine for imparting a relative rotation to said head and the work to be threaded in axial alignment therewith. Initially, the chasers are at their outward

limits of radial movement so as to clear the work, but by moving the lever X longitudinally inward, all of said chasers are simultaneously moved radially inward until the dog S engages the shoulder of the groove R'. The exact dimension of the work is determined by the relation of the shouldered groove R' to the cone N² and this in turn is determined by the adjustment of the collar R with respect to the sleeve N. Therefore, if the diameter of the work is to be enlarged, the collar R may be turned so as to screw the same away from the cone N²; or if the work is to be decreased in diameter, the collar R may be screwed in the opposite direction so as to approach the cone N². Such adjustment is facilitated by providing the collar R with a graduated flange portion R² overlapping the inner end of the sleeve N and rotatively adjustable with respect to an index line R⁴ thereon.

70 After the parts are suitably adjusted for the particular dimension of work and the lever X is moved to force the chaser blocks radially inward, the threading operation is effected by the relative rotation of the die head and the work. At the desired point a suitable stop (not shown) will arrest the longitudinal movement of the shank member D, while the continued relative rotation of the head and work will draw outward the member A. This movement is permitted by the yielding of the springs K and K', but as the pin T is attached to the flange E it will remain longitudinally stationary. Thus the cone T' on said pin will ride over the oblique face S³ of the dog, drawing said dog radially inward and releasing engagement between the same and the shoulder of the groove R'. This will permit the springs U to quickly move the sleeve N longitudinally outward, which will withdraw the cone face N² from engagement with the oblique faces O³ of the chasers. At the same time the cone face N² bearing against the outer ends of the thrust rods P will move the same inward causing the positive actuation of the chaser blocks radially outward. This outward movement is facilitated by providing a slight clearance between the ends of the rods P and the cone N² so that the latter will strike a hammer blow, its momentum assisting in overcoming any resistance of the chasers.

75 It will be understood from the description as above that the manufacturing of the die head is greatly simplified over that of constructions heretofore used. In the first place, the number of parts is reduced and all of these parts may be formed by simple machining operations such as turning, boring and milling. There are no cams or eccentric or irregularly curved surfaces to machine. The construction is also one which secures great accuracy in the work produced

and this accuracy is not lost by wear incident to the use of the tool. Therefore, the construction is an exceedingly practical one which fills a long felt want in the art.

5. What I claim as my invention is:

1. The combination with a cylindrical head having radially extending guide-ways at the outer end thereof, of chaser blocks slidably engaging said guide-ways, a sleeve surrounding said head and longitudinally slidably thereon, being provided with an annular groove forming a conical inner face for engaging the outer ends of said chaser blocks, an extension for said sleeve adjustable longitudinally with respect thereto, and a locking dog for engaging said extension to hold said chaser blocks at a predetermined inner limit of adjustment.

2. The combination with a cylindrical head having radially extending guide-ways at the outer end thereof, chaser blocks slidably engaging said guide-ways, and a sleeve surrounding said head and longitudinally slidably thereon, said sleeve being provided with an annular groove forming an uninterrupted conical inner face for engaging the outer ends of said chaser blocks, said conical face being adapted to permit movement of said chaser blocks without rotational movement of said sleeve.

3. The combination with a cylindrical head having radial guide-ways at the outer end thereof, of chaser blocks slidably engaging said radial guide-ways, a sleeve surrounding said head and grooved to provide a conical face for engaging the outer ends of said chaser blocks to move the same radially inward when said sleeve is moved longitudinally on said head in one direction, and means interposed between said sleeve and chaser blocks for positively moving the latter radially outward when said sleeve is moved longitudinally in the opposite direction.

4. The combination with a cylindrical head having radial guide-ways at the outer end thereof, of chaser blocks slidably engaging said radial guide-ways, a sleeve surrounding said head and longitudinally slidably thereon, said sleeve having an internal groove providing oppositely inclined cone faces, one of said faces engaging the outer ends of said chaser blocks to move the same radially inward in one direction of movement of the sleeve, and thrust rods slidable in said head and extending between the opposite cone face of said sleeve and the respective chaser blocks in a direction to move said blocks radially outward when said sleeve is moved to relieve pressure on the outer ends of said chaser blocks.

5. The combination with a cylindrical head having radial guide-ways at one end thereof, of chaser blocks slidably engaging said radial guide-ways, a sleeve surrounding

said head and longitudinally slidable thereon, said sleeve having an annular groove providing oppositely inclined cone faces, one of said faces engaging the outer ends of said chaser blocks to move the same radially inward when the sleeve is moved longitudinally in one direction and rods slidable in said head, each extending in a direction oblique to one of said radial guides, the outer ends of said rods being in operative relation to the opposite cone face of said sleeve, and the inner ends engaging the respective chaser blocks to impart thereto a radial outward movement.

6. The combination with a cylindrical head having a radial guide-way therein, of a block slidably engaging said guide-way, a sleeve surrounding said head and longitudinally slidable thereon, said sleeve being grooved to provide oppositely inclined faces oblique to the axis of said head, one of said faces engaging the outer end of said block to move the same radially inward, and a thrust rod slidable in said head arranged in a direction which is oblique to said radial guide and transverse to the opposite oblique face in said sleeve, said rod being actuated by said sleeve when moved in a direction to relieve pressure on the outer end of said block, and the inner end of said rod actuating said block in a radially outward direction.

7. The combination with a head having a radially extending guide-way therein, of a block slidably engaging said guide-way, a sleeve surrounding said head and longitudinally slidable thereon, said sleeve being grooved to form oppositely inclined faces, one of said faces engaging the outer end of said block to move the same radially inward, a thrust rod slidable in said head in a direction transverse to the opposite of said oblique faces and oblique to said radial guide, the inner end of said rod engaging an oblique face on said block to move the same radially outward.

8. The combination with a head having a radial guide-way therein, of a block slidably engaging said guide-way, a sleeve surrounding said head and grooved to form oppositely inclined oblique faces, one of said faces engaging the outer end of said block to move the same radially inward when said sleeve is moved longitudinally in one direction, and means for positively moving said block radially outward when said sleeve is moved longitudinally in the opposite direction, said means comprising a rod extending transverse to the opposite of said oblique faces of the sleeve and in a direction oblique to said radial guide, and an oblique face on said block engaged by the inner end of said rod.

9. The combination with a head having a radial guide-way therein, of a block slidably

engaging said guide-way, a sleeve surrounding said head having a conical face for engaging the outer end of said block to move the same radially inward upon the longitudinal movement of said sleeve, said sleeve having also an oppositely inclined conical face, and means interposed between said opposite face and said block to move the latter radially outward when said sleeve is moved to relieve pressure on the outer end of said block, said means providing a slight clearance to impart an impact from said sleeve thereto.

10. The combination with a hollow cylindrical head having a radial guide-way therein, of a shank longitudinally slidably engaged by said head, a flange on said shank forming an abutment for one end of said head, a block slidably engaging said radial guide-way, a sleeve surrounding said head and grooved to form a conical face for engaging the outer end of said block to move the same radially inward when said sleeve is moved longitudinally, a dog radially slidably in said head and engageable with a locking shoulder in said sleeve, and means operated by an outward movement of said head away from said abutment flange for withdrawing said dog from engagement with said locking shoulder.

11. The combination with a head having radial guide-ways therein and blocks slidably engaging said guide-ways, of a sleeve surrounding said head and having a conical face for engaging the outer ends of said blocks to move the same radially inward, a shank on which said head is longitudinally slidably mounted, a flange on said shank forming an abutment for the inner end of said head, means for resiliently pressing said head against said abutment, a dog radially

slidable in said head and engageable with a locking shoulder in said sleeve to hold the latter from longitudinal movement, a pin secured to said abutment flange extending through an aperture in said dog and provided with an oblique face for withdrawing said dog from engagement with said locking shoulder upon the relative longitudinal movement of said head and shank. 50

12. The combination with a shank having a flange or collar thereon, of a cylindrical head slidable upon said shank and abutting against said flange or collar, studs secured to and projecting from said flange to engage longitudinal recesses in said head on diametrically opposite sides thereof, springs sleeved on said studs and abutting against shoulders thereon at one end, bushings in said recesses surrounding said studs and forming abutments for the opposite ends of said springs, blocks slidably engaging radial guides in said head, a sleeve surrounding said head and having a conical face for engaging said blocks to actuate the same radially, pins projecting inward from said sleeve through slots in said head and intersecting longitudinal recesses in said head, springs housed within said recesses abutting at one end against said pins and at their opposite ends against stationary abutments in said head, a dog radially movable in said head and engageable with a locking recess in said sleeve, and a pin secured to said flange or abutment projecting therefrom and slidably engaging a registering aperture in said head, said pin having a conical portion for engaging said dog to actuate the same radially inward when said head is moved longitudinally with respect to said shank. 75 80

In testimony whereof I affix my signature.
CONRAD JOBST.
